UNITED STATES PATENT OFFICE.

JOSEPH O'NEIL, OF TAYLORSTOWN, PENNSYLVANIA.

PUMP.

SPECIFICATION forming part of Letters Patent No. 602,869, dated April 26, 1898.

Application filed February 17, 1897. Serial No. 628,793. (No model.)

To all whom it may concern:

Be it known that I, JOSEPH O'NEIL, a citizen of the United States, residing at Taylortown, in the county of Washington and State 5 of Pennsylvania, have invented or discovered new and useful Improvements in Pumps, of which the following is a specification.

In the accompanying drawings, which make part of this specification, Figure 1 is a broken 10 vertical section showing that portion of my apparatus which adapts the pump to use with a wire line. Fig. 2 is a like view of the pumping apparatus proper. Fig. 3 is a like broken 15 vertical section, on an enlarged scale, of the locking apparatus, showing the springs compressed. Fig. 4 is a plan view of the same. Fig. 5 is a section on line 5 5 of Fig. 3. Fig. 6 is a side elevation of the interior apparatus of the fluid-distributer. Fig. 7 is a vertical 20 section of Fig. 6. Fig. 8 is a vertical section of the shell of the fluid-distributer.

The purpose of my invention, generally stated, is to devise a pumping apparatus having two pistons of equal diameter and so arranged and combined with accessory mechanism that a wire line may be used in pumping in place of the ordinary sucker-rods. To accomplish this purpose, I so arrange my mechanism that the fluid will automatically 25 make a downdraft on the wire line and so keep the same taut on the downward stroke of the pump. My mechanism may be used with the ordinary sucker-rods, but it is not primarily intended for such use. The apparatus 30 is peculiarly adapted for use in oil-wells, but can be used in water and other wells.

In the several drawings, which make part of this specification, 2 is the tubing of an oil-well.

40 3 is the lower or standing valve of the ordinary working barrel 4.

5 is the pump-piston proper, having the usual cups.

6 is the working or upper valve.

45 7 is the valve-rod.

The tubing at its upper end is screwed to a coupling 8, which in turn is screwed to the lower end of the shell 9 of a fluid-distributer. The upper end of the fluid-distributer is likewise 50 screwed to another section of the tubing.

The construction of the fluid-distributer is clearly seen in Fig. 8. It has a longitudinal

passage extending along its left side marked 8^a. On the side of the fluid-distributer is a spring-seated valve 8^b, held open by the pressure of the fluid, as hereinafter described. The valve-passage 8^c communicates with the interior of the fluid-distributer.

I will now describe the mechanism built up in the interior of the fluid-distributer. 60 This mechanism is preferably made of a number of pieces for convenience in manufacturing and assembling. At the lower end of the distributer is the piece 9', having lateral openings 9^a 9^a. This piece is threaded at its lower 65 end into a sleeve 10, which in turn is threaded at its lower end into the upper end of the working barrel 4. The joint between the upper end of sleeve 10 and coupling 8 is packed at 11. The valve-rod 7 passes through 70 the piece 10. Screw-threaded to and supported by the piece 10 is stuffing-box 12, packed at 12' and which acts as a support for the stem 13 of vertical spring-seated valve 13^a. Said vertical valve 13^a is substantially 75 opposite valve 8^b. 14 is the valve-seat for said valve 13^a and has vertical openings 14^a 14^a. Said valve-seat 14 is threaded to the lower end of a supporting-piece 14^b, which in turn is threaded to an auxiliary working barrel 80 15, in which moves draft-piston 16.

17 is suitable packing at the upper end of valve-seat 14. Valve-rod 7' extends from piston 16 to subpiece 18, to which it is screwed, by which connection is made with jar 19, 85 above which is attached the wire cable.

I will now describe the locking mechanism for holding in place the various devices contained in the fluid-distributer and the auxiliary working barrel 15.

90 20 is a casting, shown as hexagonal and having lateral ports 20^a on four of its sides and having secured to the other two sides the leaf-springs 21 21. The casting 20 has a depending bottom flange 20^b, by which it is 95 threaded to the auxiliary working barrel 15, in which plays the draft-piston 16.

22 is a short pipe-section passing loosely through the center of casting 20 and screwed to cross-head 23, which has side slots 23^a 23^a, 100 through which pass springs 21 21. Subpiece 18 rests loosely upon top of pipe 22.

24 is a collar connecting two of the sections of tubing, said collar having an internal pe-

ipheral flange 24^a, against which the upper ends of springs 21 21 are normally locked.

The operation of the various devices will now be described. As the pump-piston 5 rises the oil in the bottom of the well will float the ball in the standing valve 3, and the oil will fill the space below the pump-piston 5. On the downstroke of the pump the working valve passes down through the column of oil in the tubing, and as the draft-piston descends the oil resting thereon raised by previous strokes of the pump descends with said draft-piston, and the oil standing in the tubing follows, flowing down through lateral ports 20^a 20^b, thus keeping the space above the draft-piston charged with oil. It should be premised that when the pump is first started it is primed by pouring in several buckets of oil, so that there may be a sufficient weight upon the draft-piston 16 to keep the wire line taut until the pump is fully working. After the pump is fully working it will be seen that the upper surface of the draft-piston 16 has the full pressure of the 25 column of oil upon it, and this pressure will tend on the downstroke of the pump to return the pump-piston proper and the draft-piston to their appropriate places and keep the wire line taut. The resistance on the under side of the draft-piston 16 is practically 30 *nil*, as the chamber immediately below said piston is kept free from oil by valve 13^a. Should, however, any oil seep into said chamber, it will be expelled on the downward movement of the piston and the pressure on the 35 upper side of the draft-piston 16 be removed. This expulsion is accomplished by the fact that the valve 13^a will yield against the pressure of the oil which has leaked in, and the 40 oil will pass through the openings 14^a 14^b and out into the well through the side valve 8^b.

When it is desirable to pull out the pump and the mechanism connected with and above the same, it is accomplished by pulling up 45 draft-piston 16 until it strikes against the lower end of pipe-section 22, which is secured

to cross-head 23. The upward movement being continued, cross-head 23 rises, compressing the bowed springs 21 21 until their upper ends slip inwardly past the flange 24^a, and the lock heretofore made between said flange and the upper ends of said springs is released. The fluid-pressure on the inside of the fluid-distributer now seats valve 8^b and prevents the escape of oil from the tubing, and thus 55 avoids repriming the valve.

Various changes may be made in the form, arrangement, and proportion of the various parts, while still preserving the spirit of my invention, and such modifications I propose to cover in the annexed claims.

Having described my invention, I claim—

1. The combination of a working barrel; a piston working therein; an auxiliary pump-barrel; a draft-piston working therein; a 65 valve-rod connecting said pistons and a valve-vented chamber immediately below the draft-piston for the purpose of relieving the under side of said piston from pressure on the downward movement of the pump.

2. In pumps the combination of a double piston; a lower piston and an intermediate fluid-distributer provided with a passage to pass the fluid up the well and a valve-controlled discharge-passage to relieve the pressure beneath the upper piston.

3. In pumping devices, a lock, consisting of a base-piece; springs attached to said base-piece; a shoulder on the connecting-collar between the well-tubing and the pumping device, said shoulder engaging said springs when the pumping device is in position, and a cross-head, through which said springs pass, loosely mounted on the valve-stem, and fitted, to be forced up, and release said springs from 85 engagement with said shoulders.

In testimony whereof I have hereunto set my hand this 21st day of January, A. D. 1897.

JOSEPH O'NEIL.
